UNITED STATES PATENT OFFICE.

EDWARD M. EK, OF PROVIDENCE, RHODE ISLAND.

HARNESS MOTION FOR LOOMS.

Application filed January 15, 1921. Serial No. 437,410.

To all whom it may concern:

Be it known that I, EDWARD M. EK, a citizen of the United States, residing at Providence, in the county of Providence, State of Rhode Island, have invented certain new and useful Improvements in Harness Motions for Looms, of which the following is a specification.

My invention relates to improvements in harness-motions for looms.

The principal object of the invention is to provide means for operating the harnesses without the use of springs or spring-jacks whereby to economize power and reduce the strain on the harness-frames.

By eliminating excessive strain on the harness-frames the latter may be constructed of lighter and thinner stock and hence an increased number of harnesses may be used in the available space.

Another object of the invention is to provide a simple and compact pattern-mechanism for controlling the shifting of the harnesses in accordance with a predetermined order.

Another object of the invention is to provide a wide range of control for a considerable number of harnesses in order to secure a maximum number of pattern variations.

Further objects of the improvement are set forth in the following specification which describes a preferred embodiment of the invention as illustrated by the accompanying drawings. In the drawings:

Fig. 1 is an end elevation of a well-known type of broad-loom showing my improved harness-motion applied thereto;

Fig. 2, a front view of the loom frame showing the method of suspending the harness-frames therein and connecting them with their actuating-means;

Fig. 3, an enlarged view of the side-brackets for supporting the harness-motion from the main frame of the loom, and also illustrating the arrangement of the pattern-roll or cylinder and its operating-mechanism;

Fig. 4, a similar view showing the detail of the selector-mechanism operated from the pattern-chain to control the shifting of the harnesses;

Fig. 5, a detail view of the selector-lever and the clutch-pawl or shifter-bar lock operated therefrom;

Fig. 6, a detail view of the detent-means

for holding the clutch-pawl in its different positions;

Fig. 7, a detail view of the locking-mechanism for the selector-levers and the means for operating the same;

Fig. 8, a view showing the grouped shifter-bars and their actuating-levers; and

Fig. 9, a detail view of the operating-mechanism for the actuating-levers.

Referring first to Fig. 1 of the drawings, F designates the main frame of the loom; B the breast-beam at the front thereof; and L the lay carried by the oscillating arms 1. The warp-beam W is supported at the rear of the loom; the take-up or winding-on roll R at the front, below the breast-beam B; and C indicates the cloth being wound thereon. The crank-shaft S extends transversely across the frame F and is driven from suitable power-devices, not herein shown, to reciprocate the lay L by means of the pitmen P connected to the cranks. On the outer end of the crank-shaft S is the usual hand-wheel G for turning the loom over by hand.

Referring now to Figs. 3 and 4, a plate or brace 2 is bolted to the central portion of one of the sides of the loom frame F, and reaching forwardly and upwardly therefrom is an elbow-shaped arm 3, see also Fig. 1. At the upper end of the arm 3 is a rectangular pad 4 which is slotted on its side to receive a plate 5 bolted thereto, see Fig. 3. The plate 5 serves as a support for a pair of levers 6 and 7 which are pivoted thereon by means of bolts 8 to adapt them to be oscillated from the crank-shaft S of the loom to transmit motion to the shifter-bars 10 which actuate the harnesses H.

Referring to Figs. 8 and 9, the actuating-levers 6 and 7 for the shifter-bars 10 are operated from two oppositely-moving rocker-shafts 11 and 12 which receive their motion from the crank-shaft S. The shafts 11 and 12 are journaled in a bearing 13 on an arm 14 extending rearwardly from the plate or brace 2; the shaft 11 being hollow or tubular in cross-section with its companion shaft 12 arranged concentrically therein. Mounted on the inner end of the hollow shaft 11 is a rocker-arm 15 secured rotatively therewith by a pin 17; and a second rocker-arm 16 is similarly secured to the end of the interior shaft 12 which projects beyond the end of the shaft 11. Pivoted to the outer ends of the rocker-arms 15 and 16

16 by means of bolts 18 are two links or connecting-rods 19 which are likewise pivotally connected at 20 to the actuating-levers 6 and 7. The tubular shaft 11 carries another 5 rocker-arm 21 on its outer end, see Fig. 9, the hub of said arm being split and clamped to the shaft by means of a binder-screw 23. Outwardly beyond the arm 21 is a fourth rocker-arm 22 secured fast by means of a 10 pin 24 to the interior shaft 12 which projects beyond the end of the shaft 11. The arms 21 and 22 are connected to be rocked in opposite directions from a pair of oscillating cam-levers 25 and 26.

15 The cam-levers 25 and 26 are pivoted on a stud 27, which projects from a plate 28 fastened to the side of the loom-frame F, and are formed near their upper ends with ring-shaped enlargements 29 surrounding 20 the crank-shaft S. The rings 29 are formed with inwardly-projecting ears 30 carrying studs 31 on which are journaled suitable cam-rolls or bowls 32. Each of the cam-levers 25 and 26 carries a pair of rolls 32 25 disposed in diametrically opposite relation to the axis of the crank-shaft S. Rotatively secured to the crank-shaft S are two cams 35 and 36 arranged in offset relation to the axis of the shaft. The peripheries of the 30 cams 35 and 36 are formed with opposite concentric faces 37 and 38 and opposite eccentric faces 39 and 40 adapted to engage with the rolls 32 on the levers 25 and 26. As the cams 35 and 36 are rotated with the 35 crank-shaft S in the direction indicated by the arrow α , Fig. 9, the levers 25 and 26 will be oscillated in alternately opposite directions with a dwell at the end of each stroke. The periphery of the cams is divided into four parts of substantially equal 40 extent so that as the cams turn through a half revolution with the rolls 32 bearing on the concentric faces 37 and 38 the levers 25 and 26 will remain at rest; while during 45 the next half revolution the rolls 32 will ride on the eccentric faces 39 and 40 to rock the two levers in opposite directions. The cam-levers 25 and 26 are formed on their adjacent sides with projecting ribs 41 and 50 42 arranged concentric with their axis of oscillation and provided with bearing-faces which slide one against the other during the oscillation of the levers to steady them in their movement. At the upper ends of the 55 levers 25 and 26 are slots 44 which are engaged by rollers 45 journaled on studs 46 projecting from the ends of the rocker-arms 21 and 22. As the cam-levers 25 and 26 are oscillated from the cams 35 and 36 60 the rollers 45 slide in the slots 44 and in this manner motion is communicated to the rocker-arms 21 and 22 to oscillate the shafts 11 and 12 and the arms 15 and 16.

65 Referring now to Figs. 1 and 8, the shifter-bars 10 for the harness-frames H are sup-

ported in a sort of cage or frame-work K mounted at the side of the loom above the plate 2. The frame K comprises two opposite brackets or uprights 48 fitted across the top of the plate 2, see Fig. 4, and connected by a cross-strut 49 bolted thereto. The cross-strut 49 is bolted or otherwise fastened to the plate 2 by suitable means not herein shown in detail. Extending horizontally between the brackets or uprights 48 are two pairs of upper and lower guide-bars 50 which are bolted to the brackets at 51 and 52. The bars 50 of each pair are spaced apart in parallel relation and the shifter-bars 10 are adapted to slide up and down between them. The actuating-levers 6 and 7 extend across the series of bars 10 and are held in place thereagainst by vertical guide-strips 47 fastened to the ends of the horizontal guide-bars 50 by the bolts 52. As shown in Figs. 4 and 8, each shifter-bar 10 is constructed from two narrow strips of metal arranged in parallel, spaced relation and connected at their ends by cylindrical studs 53 secured to the strips by rivets 54. The shifter-bars 10 are held in spaced-apart relation in the cage or frame K and guided in their movement by means of a series of suitable cross-pins 55 extending between the guide-bars 50. Connected to the studs 53 90 at the ends of the shifter-bars 10 are cords or wires 56 and 57 leading to the harness-frames H, see Fig. 2. The cords 56 from the upper ends of the shifter-bars lead over sheaves or pulleys 58 and 59 supported on the arch-members 60 of the loom. Referring to Figs. 1 and 2, the two arches 60 are bolted to the top of the brackets or uprights 48 on one side of the loom and supported from the main frame F at the opposite side. The sheaves 58 are journaled on rods or shafts 61 extending between brackets 62 fastened to the arches 60, while the sheaves 59 of the other set are journaled on rods 63 extending between the arches. The number of sheaves employed in each set corresponds to the number of harnesses to be used in the loom and the adjacent sheaves in each series are held in place on their rods by suitable collars 64 at the ends, see Fig. 1. The cords 57 from the lower ends of the shifter-bars 10 lead down around guide-sheaves 65 supported from brackets 66 attached to the loom-frame F, see Figs. 1 and 2, and thence pass around sheaves 67 carried by brackets 68 attached to the lower cross-strut 69. The harness-frames H are constructed with the usual cross-members h , h' to which the ends of the wires or cords 56 and 57 are fastened, and extending between the cross-members are the wire heddles h' of well-known arrangement. Each shifter-bar 10 is connected in the above-described manner with one of the harness-frames H and it will be understood that as the shifter-bars are recipro- 130

cated up-and-down in their guideways the respective harness-frames connected thereto will be raised and lowered therefrom.

The shifter-bars 10 are adapted to be connected at intervals with their actuating-levers 6 and 7 by means of a selector-mechanism arranged as next described. Referring to Fig. 4, each shifter-bar 10 carries a rockable clutch-pawl 70 disposed between its side-strips and pivoted on a cross-pin 71 located at a point midway of its ends. The pawl 70 is formed at top and bottom with undercut hook-like projections or toes 72 and 73 which are adapted to engage respectively with the beveled edges of the upper and lower actuating-levers 6 and 7.

Referring to Figs. 4 and 5, when the pawl 70 is rocked forward at the top its toe 72 will be carried into position to hook over the upper edge of the lever 6; and when it is rocked in the opposite direction its lower toe 73 will be thrown into position to engage the under edge of the lever 7. It will be noted from Fig. 4 that the shifter-bars 10 are each formed with a projection 74 at the center, see also Fig. 8, which is undercut at top and bottom to adapt it to hook across the lower beveled edge of the actuating-lever 6 and the upper edge of the lever 7. It will thus be seen that when the pawl 70 is rocked forward at the top, as shown in Fig. 5, it will clutch the lever 6 between its toe 72 and the projection 74; while with the pawl rocked forward at the bottom the toe 73 will cooperate with the projection 74 to lock the lower lever 7 to the shifter-bar 10.

Referring to Fig. 4, the pawls 70 are operated from a series of selector-levers 75 arranged in alignment opposite the row of shifter-bars 10 and controlled from a pattern-chain D of usual type. The several levers 75 are pivoted on a horizontal shaft 76 carried by a pair of rockable arms 77 arranged outside the brackets or uprights 48. The rocker-arms 77 are secured to a lower cross-shaft 78, see Fig. 4, which is journaled in bearings in the brackets 48. The cross-shaft 76 extends between the upper extremities of the arms 77, its ends being secured therein by set-screws 80, and passing through suitable slots 81 in the brackets 48 to permit the shaft to move back and forth with the arms. The rocker-arms 77 are oscillated from a cam 82 whereby to carry the selector-levers 75 toward the pawls 70 to shift the latter and to then withdraw the levers away therefrom. The cam 82 is fast on a shaft 84 which is driven from the crank-shaft S through a train of gearing shown in Fig. 1. On the end of the crank-shaft S is a bevel-gear 85 which meshes with a gear 86 on the lower end of an inclined shaft 87. The lower end of the shaft 87 is journaled in a bearing 88 swiveled on

the crank-shaft S, while its upper end turns in a bearing 89 attached to one of the brackets or uprights 48. At the upper end of the shaft 87 is a bevel-gear 90 meshing with a corresponding gear 91 on the outer end of the cam-shaft 84. Referring to Fig. 4, the cam 82 is of double-contour type having a main cylindrical portion 92 with a cut-out 93 in its periphery, and a smaller cylindrical hub 94 with a star-point 95 arranged diametrically opposite the cut-out. On one side of the rocker-arm 77 is a curved finger 97 carrying a roller or bowl 98 which travels on the main cylinder 92 of the cam; while a second bowl 99 carried at the upper end of the arm 77 is adapted to travel over the smaller contour of the cam. The cam 82 is rotated in the direction indicated by the arrow b, Fig. 4, and normally, as the opposite rollers 98 and 99 travel on the cylindrical portions of the cam, the rocker-arm 77 will remain at rest. When, however, the point or projection 95 of the cam comes into action on the roll 99 of the rocker-arm the latter will be rocked in the direction indicated by the arrow c, Fig. 4, and then returned to first position again with a quick action. As before stated, the rocker-arm 77 and its opposite companion arm carry the shaft 76 on which the selector-levers 75 are mounted and as the two arms are rocked inwardly toward the shifter-bars 10 the levers are carried into position to actuate the clutch-pawls 70 in the manner as hereinafter more fully explained.

The forward ends of the selector-levers 75 are of fork-shape with upper and lower fingers or projections 100 and 101 rounded off at their ends and adapted to engage the edges of the pawls 70. To insure that the ends of the levers 75 may engage properly with the appropriate pawls 70 operated therefrom the forked portions of the levers are held in a comb-like rack or grating J. The grating J consists of upper and lower parallel bars 103 extending horizontally between the brackets 48 and attached thereto by suitable sockets 104. Held in spaced relation along the bars 103 are vertical teeth or tines 105 constructed of relatively thin strips of metal which are arranged between the adjacent levers 75 of the series to space them apart and maintain them in opposite alignment with their respective pawls 70. A comb or rack O is also provided for the same purpose at the outer ends of the levers 75. As shown in Fig. 4, the comb O consists of a row of vertical pins 107 supported on a bar 108 extending between the brackets 48.

As shown in Figs. 4 and 5, the upper finger 100 of each selector-lever 75 strikes against the rounded rearward edge of its opposite pawl 70 to rock the upper end of the pawl forward, and the lower end of the pawl is cut away with a notch 106 to provide clearance for the lower projection 101

of the lever 75 during this action. The levers 75 engage with the upper portions of the pawls 70 when the forward ends of the levers are lowered to the position of the 5 first lever shown in Fig. 4. Stated another way, the levers 70 are moved forward with their rear ends raised by the pattern-mechanism M to shift the upper ends of the pawls 70 on the shifter-bars 10 forward into locking 10 engagement with the upper actuating-lever 6. When, however, the pawl 70 is to be shifted into the opposite position to lock its shifter-bar to the lower actuating-lever 7 the rear end of the lever 75 is lowered until 15 it rides on a cross-rod 110 which extends between the uprights 48. When the rear end of the lever 75 is lowered its forked forward end will be raised to bring its bottom projection 101 into position to engage 20 with the shouldered portion 111 of the pawl 70, see Fig. 4. With the lever 75 in this second operative position, that is with its forked end raised, the upper projection 101 will be drawn back out of the way so 25 as not to interfere with the movement of the pawl 70 as its lower end is pushed forward and its upper end swings back. The pawl 70 is held in its two different positions against accidental movement by means of a 30 yielding detent-spring 112. As shown in Figs. 4 and 6, the spring 112 is of hairpin shape with the ends of its legs fastened in a block 113 held between the sides of the shifter-bar 10 and fastened thereto by a 35 rivet 114. The upper cross-bar 115 of the spring 112 is adapted to ride across a rounded projection 116 formed in a cut-out portion 117 at the center of the pawl 70. As the spring snaps over the projection 116 and 40 seats in the groove at either side thereof it holds the pawl from accidental displacement while allowing it to be shifted under the action of its selector-lever 75.

The levers 75 are raised and lowered into 45 different selective positions by means of the pattern-mechanism M before referred to and now to be described in detail. Journaled in bearings 118 bolted to the sides of the brackets 48, see Fig. 3, is a horizontal cross-shaft 119 carrying the pattern-roll or drum 120 shown in Fig. 4. The roll 120 is of polygonal contour on its periphery and provided with longitudinal grooves 121 cut into its face. The roll 120 serves as a sprocket for 50 driving the pattern-chain D, the latter consisting of a series of slats or staves 126 linked together at their ends by endless chains 127, see Fig. 1. The slats 126 are of wedge-shape in cross-section to adapt them 55 to seat in the grooves 121 of the roll 120 as the chain D rides thereover. Referring to Fig. 1, the slats 126 are provided with a series of threaded holes 128 spaced along 60 their length and adapted to receive lifter-pins 130 which are screwed thereinto. The

pins 130 are arranged in alignment with the selector-levers 75 overlying the roll 120 and are adapted to act on the levers to raise their outer ends in the manner as shown in Fig. 4. By applying the pins 130 to the 70 pattern-chain D in accordance with the pattern to be reproduced the selector-levers 75 are actuated therefrom with the required order of sequence.

The pattern-roll 120 is driven with an intermittent rotation through a Geneva-motion N operated from the cam-shaft 84, see Fig. 3. On the shaft 84 is a wheel or disk 135 having a hub 136 formed with an opening 137 cut into its side. Opposite the opening 137 is a stud or pin 138 projecting from the side of the disk 135 and adapted to enter the radial slots 139 in a gear-wheel 140 fast on the end of the roll-shaft 119. The Geneva-gear 140 is formed with fan-shaped teeth 141 having concaved ends adapted to bear against the periphery of the hub 136 of the disk 135. As the wheel or disk 135 turns in the direction indicated by the arrow d, Fig. 3, its pin 138 riding into one of the slots 139 80 will turn the gear 140 while the points of its teeth travel through the opening 137. As the pin 138 passes out of the slot 139 the end of the next tooth 141 comes into engagement with the hub 136 of the disk 135 to hold the gear from further movement until the next 85 rotation of the wheel 135. As shown in Fig. 3, the gear 140 is provided with six teeth so that at each rotation of the wheel 135 it is turned through sixty degrees or one 90 sixth of a circumference. The spacing of the grooves for the slats of the pattern-chain D has an equal ratio with the spacing of the teeth in the gear 140 and hence at each turn of the roll 120 one series of lifter-pins 130 is brought into vertical position, 95 as shown in Fig. 4, to cause them to raise their respective selector-levers 75.

To insure a positive and efficient action of the selector-levers 75 on the clutch-pawls 110 100 means are provided to lock the levers in either raised or depressed position as they move forward to engage the pawls. Referring to Fig. 4, it will be noted that the rearward ends of the levers 75 are dovetailed or 105 formed with notches 142. Adapted to engage the notches 142 when the ends of the levers 75 are raised is a cross-rod 143 which is 110 slidable in slots 144 in the side-brackets 48. The rod 143 extends across the rearward ends of the several levers 75 and is held in a pair of opposite arms 145, see Fig. 7, which reach outwardly at the sides of the brackets 48 above the cam-shaft 84. The inner ends of the arms 145 are pivoted to 115 toggle-links 146 which, in turn, are pivotally mounted on the cross-rod or shaft 76 which carries the levers 75. Mounted at either end of the cam-shaft 84 is a cam 147 120 adapted to actuate a pivoted lever 148 with 125 130

a rising and falling motion. The cam 147 takes the form of a segment of a circle having a concentric face 149 which engages first one arcuate face 150 and then the other 151 on the forked end of the lever 148 pivoted at 153 to the bracket 48. At the ends of the arcuate faces 150 and 151 are beveled faces 152 across which the inclined sides of the cam ride to impart a smooth, easy rocking motion to the lever 148. Projecting from a lug at the top of the forked end of the lever 148 is a stud or pin 154 which engages a slot 155 in the arm 145. As the lever 148 is raised and lowered with a relatively slow movement its pin 154 will cause a corresponding rise and fall in the arm 145. As the arm 145 is drawn down it will rock the link 146 at its end in the direction indicated by the arrow *e*, Fig. 7, and hence the arm 20 will be drawn inwardly in the direction indicated by the arrow *f*, Fig. 7. It will be understood that the arm 145 is arranged opposite to a similar arm which is operated in the same manner from another cam and link-motion as above described.

It has been explained that the two arms 145 carry the locking-bar or rod 143 at their ends and the bar is moved by and with the arms to carry it into locking-engagement with the selector-levers 75. As the links 146 draw the arms inwardly the bar or rod 143 is engaged with the notches 142 in the ends of the up-tilted levers 75, see Fig. 4, and it will also be noted that the bar 143 is carried into position across the top of the levers which are depressed. That is to say, the bar 143 not only locks the several levers 75 whose notches it engages but it also holds down the other series of depressed levers to prevent them from tilting or moving out of place. When the shaft 76 carries the levers 75 forward, due to the rocking motion of the arms 77, the links 146 pivoted on the shaft will draw the bar 143 forward with the levers and hence the latter will be held positively in their selective relation throughout their operative stroke. As the levers 75 are carried back again away from the pawls 70 the cams 147 act to lift the fork-levers 148 and the latter raise the arms 145 to swing their links above the shaft 76 so that the rod or bar 143 is carried back to release the levers 75 to allow them to be shifted in position once more as required.

Having now described the construction and arrangement of my improved device in detail its method of operation will next be explained. The crank-shaft *S* is driven from any suitable source of power and the pitman *P* are reciprocated thereby to oscillate the lay *L* back and forth in the usual manner. Referring to Fig. 9, the cam-shaft *S* turns in the direction indicated by the arrow *x* and the cams 35 and 36, being fast thereon, are rotated therewith to oscillate the levers 25 and 26 back and forth across center with a slight dwell at the end of each stroke. The cams are so timed in relation to the cranks on the shaft *S* that the levers 25 and 26 oscillate past each other across center both during the forward and rearward stroke of the lay, or in other words, the levers are reversed in position once as the lay moves forward and again as it moves back. As the cam-levers 25 and 26 are rocked back and forth in this manner the rocker-arms 21 and 22 are operated therefrom and likewise moved across center, as indicated by the arrows *y* and *z* in Fig. 9, to reverse their positions. The rocker-arm 21 is fast on the tubular shaft 11 and hence it will oscillate this shaft to rock the lever 15 in the same direction, as indicated by the arrow *v* in Fig. 9; while the arm 22 fast on the shaft 12 will act therethrough to rock the arm 16 in the opposite direction as indicated by the arrow *w* in Fig. 8. The rocker-arms 15 and 16 are connected respectively with the actuating levers 7 and 6 which reciprocate the shifter-bars 10 and the method of operation of these levers is as follows: Referring to Fig. 8, this view shows the levers 6 and 7 in horizontal position in parallel relation. Now as the rocker-arm 15 is rocked downward, as indicated by the arrow *v*, the lever 7 will be drawn down by its link 19 connected thereto; while as the arm 16 is rocked upward at the same time the lever 6 will be raised by its link 19 connected therewith. In this manner the actuating lever 6 is raised and the lever 7 depressed at each half rotation of the crank-shaft *S*, see dotted lines in Fig. 8; while at the next half rotation of the crank-shaft the levers are carried toward each other into horizontal position as illustrated by the full lines in Fig. 8. It has been explained that the cam-levers 25 and 26, see Fig. 9, are reversed in position at each stroke of the lay *L* and it will therefore be obvious that the actuating-levers 6 and 7 must also be shifted during both the forward and rearward stroke of the lay. The arrangement of the cams 35 and 36 in relation to the cranks of the shaft *S* is such that as the lay *L* moves forward the two levers 6 and 7 are swung toward each other into neutral position; while as the lay moves back again the levers 6 and 7 are swung apart. As before stated, the cam-levers 25 and 26 have a dwell at the ends of their stroke during the period that the rollers 32 travel over the concentric portions 37 and 38 of the cams 35 and 36, see Fig. 9, and consequently the actuating-levers 6 and 7 will also be brought to rest for an instant concurrently therewith. With the levers 6 and 7 in neutral position, as illustrated by the full lines in Fig. 8, the pause in their action occurs as the lay *L* approaches the forward end of its stroke to beat the last-

woven pick of yarn into the fell of the cloth. During this period of rest the several shifter-bars 10 are all in opposite alignment in their mean position and at this point in the 5 operation of the loom the selector-mechanism comes into action to shift the order of coupling the shifter-bars to the opposite actuating-levers 6 and 7.

It has been explained that the pattern-roll 10 120 is driven intermittently from the cam-shaft 84 which receives its motion from the crank-shaft S through the train of gearing 85, 86, 90, 91, shown in Fig. 1. The roll 120 is turned from the Geneva-motion N, see 15 Fig. 3, through a sixth of a rotation at each pick of the loom, and at each turn a new slat 126 in the pattern-chain D is brought into position beneath the outer arms of the selector-levers 75, as shown in Fig. 4. The 20 slats 126 carry the lifter-pins 130 which, as before explained, are arranged in predetermined order therealong to correspond to pattern changes to be reproduced in the fabric. As the pins 130 ride up in under the 25 levers 75 certain of the latter will be tilted upwardly at the rear while certain others will be allowed to drop down on the rest or supporting-rod 110 where no pins occur beneath them on the pattern-chain. Any desired order and sequence for raising and lowering the selector-levers 75 may be provided by a suitable arrangement of the pins 130 on the pattern-chain D, and the shifting of the levers 75 takes place while they are drawn 30 back from the clutch-pawls 70 on the shifter-bars 10, and during the time that the bars 10 are being raised and lowered by the actuating-levers 6 and 7. As the actuating-levers 6 and 7 come to rest in neutral position, as shown by full lines in Fig. 8, the selector-levers 75 will have been shifted in 35 position and will be moving forward under the action of the rocker-arms 77 carrying the shaft 76 on which the levers are mounted. It has been explained that the arms 77 are 40 rocked from the cam 82, and during their forward movement the levers 75 are locked in their predetermined correlation by the rod 143 engaging their rearward ends. The 45 rod 143 is slid into engagement with the notches 142 at the ends of the up-tilted levers 75 by the sliding action of the opposite arms 145 and also slides across the top of the depressed levers to lock all of the levers in 50 place. The arms 145 receive their motion from the toggle-action of the links 146 at their inner ends, see Fig. 7, as the levers 148 draw the arms down when rocked by the cams 147 in the manner as before explained. 55 After the levers 75 have been locked in position by the rod 143 they start to move forward in the direction indicated by the arrow f, Figs. 4 and 7, and the rod 143 is carried forward with them by the arms 145 60 which, as before stated, are connected to the 65 shaft 76. During the sliding movement of the arms 145 the rod 143 slides in the slots 144 and the pins 154 on the levers 148 slide in the slots 155, see Fig. 7.

As above stated, the selector-levers 75 70 come into action on the clutch-pawls 70 while the shifter-bars 10 are at rest in mid-position. Where a pawl 70 is rocked back at the top with its lower toe 73 hooked under the edge of the lower actuating-lever 7 75 if its respective selector-lever 75 is lowered at the front then the upper finger 100 on the forked end of the lever will engage the edge of the pawl to rock its upper leg forward, as shown in Fig. 5. Stated briefly, 80 the pawl 70 will be rocked forward at the top to release its lower toe 73 from the lever 7 and to hook its upper toe 72 across the upper edge of the actuating-lever 6. On the other hand, where the pawl 70 is already engaged with the upper lever 6, then if its selector-lever 75 moves forward with its forked end depressed, as shown in Fig. 5, 85 it will have no effect on the pawl but will allow it to remain in locking engagement 90 with the upper lever. When, however, the selector-lever 75 is shifted in position and its forked end elevated, if the pawl 70 is locked to the lever 6 then it will be rocked away therefrom and engaged with the lower 95 lever 7. Referring to Fig. 4, one of the levers 75 is here shown with its forked end raised and the forward movement of the lever in this position carries its lower projection 101 against the shoulder 111 on the 100 pawl 70 to push it forward at the bottom whereby to carry its toe 73 across the lower edge of the lever 7. It has before been explained that with the pawl 70 rocked forward at the top the actuating-lever 6 is 105 clutched or locked between the toe 72 on the pawl and the fixed projection or abutment 74 on the shifter-rod 10; while with the pawl 70 in its opposite position the lower 110 lever 7 is gripped between the bottom toe 73 of the pawl and the abutment 74 on the shifter-rod.

It will thus be seen that each shifter-bar 10 is locked to one or the other of the actuating-levers 6 and 7 in accordance with 115 the selective position of its respective selector-lever 75. The relative positions of the selector-levers 75 is determined by the setting of the lifter-pins 130 on the pattern-chain D, as before explained, it being understood that the levers 75 drop back into first position under the action of gravity after the pins ride out from in under their rearward arms. After the levers 75 have been carried forward in unison to operate 120 on the pawls 70 they are immediately withdrawn again and the locking-bar 143 is slid away from their ends to allow them to be individually shifted in position again by the 125 turning movement of the pattern-chain D. 130

In some instances a selector-lever which is depressed may remain in this position during several forward movements so that the pawl 70 operated therefrom will not be unlocked from the lower actuating-lever 7; and likewise one or more of the selector-levers may be sustained in raised position for a time by a series of lifter-pins 130 passing under its rearward arm so that any one 10 or more of the pawls 70 may remain locked to the upper actuating-lever 6 through a certain cycle of operations.

The pawls 70 are held in locked relation with the actuating-levers 6 and 7 by the engagement of the detent-springs 112 with their projections 116 and in this way the shifter-bars 10 are securely clutched to the levers 6 and 7 to be moved therewith. It has before been explained that each shifter-bar 10 is connected at top and bottom to one of the harness-frames H by means of the wires 56 and 57, see Fig. 2, and hence when one of the shifter-bars is moved upwardly under the action of the lever 6 its respective frame H will be drawn down by the wires 57; while, on the other hand, when one of the bars 10 is moved downwardly it will cause the wires 56 to raise the frame H connected thereto. It will be observed by reference to Fig. 8 that the shifter-bars 10 farthest away from the pivots 8 of the actuating-levers 6 and 7 will have the greatest rise and fall under the action of the levers and these bars are connected to the harness-frames farthest removed from the front of the loom. This provides that an increasing range of motion is imparted to the harness-frames as they progress rearwardly from the fell of the cloth so that all of the warp-yarns controlled by the bank of harnesses will be shifted sufficiently to open the shed to the full extent required for proper weaving conditions. Moreover, the arrangement of the cam-mechanism which operates the actuating-levers 6 and 7 is such that the harnesses are held in raised and lowered position with a dwell so that the shed remains open for a long enough period to insure the free passage of the shuttle without danger of interference with the warp. The operation of the selector-levers 75 takes place after each pick of the shuttle and the shifter-bars 10 are thus locked to the actuating-levers 6 and 7 in accordance with the prescribed sequence and order in which the harnesses are to be raised and lowered to reproduce the pattern in the fabric in accordance with the design laid out by the arrangement of the pins 130 on the pattern-chain D. After the pattern-mechanism has once been set the loom may be operated continuously to weave long lengths of fabric with the pattern repeated therein at regular intervals.

65 It will be observed from the above that

my invention provides a particularly simple, compact and efficient mechanism for automatically operating the harness of the loom with a positive action, without backlash or lost motion. The operating parts of the mechanism are light in weight and arranged for easy action whereby to save power and reduce the friction and wear, while also eliminating much of the vibration resulting from the movement of the heavy jacks and levers as usually employed. By reducing the strain on the harness-frames the latter may be made lighter and thinner whereby a much larger number of harnesses may be employed in the loom to allow for a wider range of pattern changes. The pattern-mechanism is particularly accurate and positive in action to insure uniform weaving without faults or blemishes in the cloth and the device is adapted to practically all types of looms and may be applied to looms already in use without material alteration in the general structure or readjustment of the parts thereof.

70 While I have herein shown and described a preferred embodiment of the device it is to be understood that various changes may be made in the structure and arrangement of the parts of the mechanism without departing from the spirit or scope of the invention; therefore, without limiting myself in this respect, I claim:

1. In a harness-motion for looms, the combination with a plurality of harness-frames, of a series of shifter-bars each connected to a harness-frame, a pair of oppositely-moving levers arranged adjacent the bars, a pawl pivoted on each shifter-bar to adapt it to rock into opposite positions to engage one or the other of the actuating-levers, a series of forked selector-levers adapted to be shifted in position to engage at different points on the pawls, pattern-mechanism for controlling the position of the selector-levers, and means to move the levers bodily into position to actuate the pawls with opposite effect thereon in accordance with the selective position to which said levers have been shifted.

100 2. In a harness-motion for looms, the combination with a plurality of harness-frames, of a series of shifter-bars each connected to a harness-frame, a pair of oppositely-moving actuating-levers, a pawl pivoted on each shifter-bar to adapt it to be rocked to engage one or the other of the actuating-levers, a series of selector-levers having fingers adapted to engage the opposite ends of the pawls, means for shifting the selector-levers to cause their opposite fingers to engage with first one and then the other end of their respective pawls, and means for bodily moving the levers into position to actuate the pawls.

110 3. In a harness-motion for looms, the com-

bination with a plurality of harness-frames, of a series of shifter-members connected to raise and lower the several frames, oppositely-moving actuating-members for shifting the shifter-members, means for interchangeably connecting the individual shifter-members with the different actuating-members, selector-members for selectively operating the connecting-means, means for shifting the selector-members into different positions to regulate their operative effect on the connecting-means, means for bodily moving the selector-members into position to actuate the connecting-means, and means to lock the selector-members in their different operative positions.

4. In a harness-motion for looms, the combination with a plurality of harness-frames, of a series of shifter-members connected to raise and lower the several frames, oppositely-moving actuating-members for shifting the shifter-members, means for interchangeably connecting the individual shifter-members with the different actuating-members, a series of selector-members for selectively operating the connecting-means, means for shifting the selector-members into different positions to vary their operative

effect on the connecting-means, means to move the selector-members bodily into position to engage with the connecting-means, and means slidably into engagement with the selector-members after they have been shifted to lock them in their operative relation.

5. In a harness-motion for looms, the combination with a plurality of harness-frames, of a series of shifter-members connected to raise and lower the several frames, oppositely-moving actuating-members for shifting the shifter-members, means for interchangeably connecting the individual shifter-members with the different actuating-members, a series of rockable selector-levers for operating the connecting-means, means to rock the selector-levers into different positions to alter their operative effect on the connecting-means, means to carry the selector-levers forward to cause them to act on the connecting-means, means for locking the selector-levers in their operative relation, and means to carry said locking-means forward with the levers during the operative stroke thereof.

In testimony whereof I affix my signature.
EDWARD M. EK.
